[57] CLAIM

The ornamental design for a ganging chair, as shown and described.

DESCRIPTION

FIG. 1 is a perspective view of a ganging chair showing my new design;

FIG. 2 is a front elevation view thereof;

FIG. 3a is a back elevation view thereof;

FIG. 3b is a back elevation view thereof, being an alternative embodiment of the design as shown in FIG. 3a;

FIG. 4 is a left elevation view thereof;

FIG. 5 is a right elevation view thereof;

FIG. 6 is a top plan view thereof;

FIG. 7a is a bottom plan view thereof; and,

FIG. 7b is a bottom plan view thereof, being an alternative embodiment of the design as shown in FIG. 7a.

The sole difference in the second embodiment, as shown in FIGS. 3b and 7b, would be the hand hole shown on the rear of the backrest. The other views of the second embodiment would be like those shown in FIGS. 1, 2, 4, 5 and 6.
